UNITED STATES PATENT OFFICE

99,162

DESIGN FOR A TRAFFIC BEACON

Emory W. Hough, Fostoria, Ohio

Application January 13, 1936, Serial No. 60,557

Term of patent 7 years

To all whom it may concern:

Be it known that I, Emory W. Hough, a citizen of the United States, residing at Fostoria, in the county of Seneca and State of Ohio, have invented a new, original, and ornamental Design for a Traffic Beacon, of which the following is a specification, reference being had to the accompanying drawing, forming a part thereof.

Fig. 1 is a side elevational view of the traffic

beacon showing my new design; and Fig. 2 is a top plan view thereof.

I claim:

The ornamental design for a traffic beacon as shown.

In witness whereof I have hereunto signed my name to this specification.

EMORY W. HOUGH.
